By J. F. Palmer
Attorney

UNITED STATES PATENT OFFICE.

JOHN FREDERICK PALMER, OF MILWAUKEE, WISCONSIN.

MOP.

Application filed June 15, 1925. Serial No. 37,320.

This invention relates to mops.

Objects of this invention are to provide a detachable mop in which a body portion is provided for the reception of the prongs from the mop, and in which the mop prongs are not weakened adjacent their points of engagement with the attachment, but are left intact for a material distance from the mop itself and are locked adjacent their extreme end, thus maintaining the integrity of the prongs and the strength thereof.

Further objects are to provide means for quickly detaching the mop from the holder which may be worked by means of a nut, and which is positive in its action and prevents inadvertent loosening of the mop.

An embodiment of the invention is shown in the accompanying drawings, in which:—

Figure 1 is a view of the mop in position 20 on the attachment with parts in section.

Figure 2 is a longitudinal sectional view at right angles to Figure 1.

Figure 3 is a detail partly in section of the upper end of the prongs.

Figure 4 is a transverse sectional view on the line 4—4 of Figure 1.

The mop comprises a plurality of strands 1 which are folded over a transversely extending bottom bar 2, and a corresponding upper bar 3. The folded portion of the strands is enclosed by means of a fabric sheath 4 which is secured on opposite sides of the bars by means of lines of stitching, as shown most clearly in Figures 1 and 2. The bars 3 have their terminals turned outwardly at right angles to form the attaching prongs 5. The extreme ends of these attaching prongs are secured together by means of a rivet 6, as shown in Figure 3. An aperture 7 is formed adjacent the ends of the prongs.

The body portion comprises a shank 8 which is apertured, as shown in Figures 2 and 4, to receive the prongs 5, and to snugly hold the prongs in sliding engagement. It is to be noted that this apertured shank 8 is elongated and houses substantially the entire length of the prongs, thus securing a very firm attachment between the prongs and the body portion.

50 The shank is provided with external threads 9 upon which a ring nut 10 is screwed, as shown most clearly in Figures 1 and 2.

Further, it is to be noted that a channel 11 is formed in one side of the shank and 55 houses a small rocker bar 12 which is provided with an upturned lower end 13. The upper

end of the rocking bar 12 is provided with a locking finger 14 adapted to enter the aperture 7.

It is to be noted that when the nut is 60 screwed into its uppermost position, that the locking finger 14 is held in position within the aperture 7 against inadvertent detachment. When the nut 10 is screwed downwardly it engages the outwardly turned end 65 13 of the bar 12, and it rocks the finger 14 out of engagement with the aperture 7, thus releasing the prongs 5 from locking engagement and permitting the withdrawal of the prongs from the body portion. 70

It is to be noted that the upper end of the body portion is provided with a slightly conical aperture 15 adapted to receive the conical portion 16 of the handle 17. A screw 18 extends into the handle and is countersunk in 75 the upper end of the body portion, as shown most clearly in Figure 2, thus temporarily locking the shank to the handle.

It is to be noted particularly that the aperture 7 in the prongs 5 is located adjacent 80 their extreme upper ends, and that the shank 8 engages the prongs throughout substantially their entire extent. This avoids the usual defects so common in mops of having the prongs weakened at their points of engagement with the body portion. 85

It will be seen that a mop has been provided in which a fabric sheath wholly encloses the metallic parts of the mop and provides an upper relatively heavy portion which may 90 be used for scrubbing if desired. Further, this fabric sheath prevents damage to the floor board or foot board or furniture in a room when the mop is used.

It will be noted further that the mop may 95 be very quickly and readily detached from the body portion by unscrewing the nut 10.

It will be seen, therefore, that a detachable mop has been provided which is of extremely rugged and substantial construction, and in 100 which the parts may be most easily operated.

Although the invention has been described in considerable detail, it is to be understood that the invention may be variously embodied and is, therefore, to be limited only as 105 claimed.

I claim:

In a mop, the combination of a mop head having a projecting tongue provided with a transverse aperture and a mop head holder 110 having a shank provided with a longitudinal aperture adapted to receive said tongue, said

shank having external threads and having a transverse aperture adapted to align with the said first mentioned transverse aperture, a ring nut surrounding said shank and cooperating with said threads, said shank having an externally located slot, a rocking bar within said slot and having an outwardly projecting cam portion, and a finger carried by said bar and adapted to be projected through 10 said transverse apertures to lock said tongue within said shank, said rocking bar being straight throughout its major portion, the straight portion of said bar being normally located below the threads throughout the entire length of the straight portion. 15

In testimony that I claim the foregoing I have hereunto set my hand at Milwaukee, in the county of Milwaukee and State of Wisconsin.

JOHN FREDERICK PALMER.
